UNITED STATES PATENT OFFICE.

HENRY P. EASTMAN, OF LIVINGSTON MANOR, NEW YORK.

TIE-STRETCHER.

1,192,771.

Specification of Letters Patent. Patented July 25, 1916.

Application filed November 7, 1914. Serial No. 870,860.

To all whom it may concern:

Be it known that I, HENRY P. EASTMAN, a citizen of the United States, residing at Livingston Manor, in the county of Sullivan and State of New York, have invented certain new and useful Improvements in Tie-Stretchers; and I do hereby declare the following to be a full, clear, and exact description of the invention, such as will enable others skilled in the art to which it appertains to make and use the same.

This invention relates to new and useful improvements in tie stretchers, and has for its principal object to provide a device which will maintain the tie in a fresh condition and eliminate wrinkles and the like, thus giving worn ties the appearance of being new.

Another object of the invention is to provide a device which may be used in pressing ties and holding the same in such a position as to avoid any wrinkling or injury thereto.

With these and other objects in view, the invention consists in the novel combination and arrangement of parts which will be fully set forth in the following specification and accompanying drawings, in which,

Figure 1 is a front view in elevation of a tie stretcher constructed in accordance with this invention, Fig. 2 is an edge view of Fig. 1, and Fig. 3 is an enlarged detail sectional view of a portion of the tie clamp.

Referring now to the drawings by characters of reference, the numeral 1 designates as an entirety a tie stretcher constructed in accordance with this invention comprising the tapered base 2. This tapered base is provided at its reduced end with the longitudinal axial bore 3 which extends part way thereinto and has communicating therewith intermediate its ends the slot 4. The enlarged end of the base 2 is provided with the beveled faces 5 to enable a number of these devices to be piled one upon the other when the same are to be used in pressing. These tapered faces 5 also serve to prevent the clamp, which will be more fully herein-after described, from sliding upwardly and releasing its hold upon the ties. The clamp hereinbefore mentioned comprises the clamping bars 6 which are connected at one end by the bight portion 7, which bight portion is enlarged to give the proper resiliency to the arms. These arms 6 are arranged so that they normally curve outwardly at their free ends, and one of the arms is slotted as at

8 to receive the turn button designated generally by the numeral 9. This turn button 9 comprises the disk 10 having formed at each end the reduced portions 11, one of which terminates in the enlarged semi-circular portion 12, while the opposite end projects through an aperture formed in the arm opposite the one in which the slot is formed to pivotally secure the button 9 in place. When these arms are to be clamped the semi-circular portion 12 is passed through the slot 8 and turned slightly as illustrated in Fig. 1. In this position it will be apparent that the same may be easily released by pressing the free ends of the arms toward each other and causing the edges of the slots to engage the edges of the disk 10, thereby causing the button to turn on its pivot 11 into such a position as to enable the ends of the arms to separate and permit the head or enlargement 12 to pass through the slot, thereby eliminating the use of more than one hand in releasing the device.

Slidable in the longitudinal bore 3 in the reduced end of the base 2 is the plunger 13 which is provided at its upper end with the cross bar 14. This plunger is also provided with the pin 15 which extends through the slot 4 and holds the plunger in the proper position. A suitable coil spring 16 is arranged to exert upward pressure against the lower terminal of the plunger 13 to force the head 14 upwardly when the tie is in place. In order to hold the plunger and cross piece 14 downwardly when a tie is to be put in position, the hook 17 is pivotally secured as at 18 to the base 2 and the upper end of the hook is arranged to engage the pin or nail 19 to hold the plunger inwardly when a tie is being put in place.

It will be apparent from the foregoing that in use the cross piece and plunger are first forced inwardly and hooked by means of the hook 17. The tie is then put in place and clamped by means of the clamp bars 6 and drawn tightly thereover. The hook is then released permitting the spring 16 to exert upward pressure on the plunger, and it will be apparent that the ties will be stretched, and wrinkles and creases removed therefrom.

While in the foregoing there has been shown and described the preferred embodiment of this invention, it is to be understood that such changes may be made in the com-

bination and arrangement of parts as will fall within the spirit and scope of the invention as defined in the appended claims.

What is claimed is:

- 5 1. A necktie stretcher comprising an elongated tapering base, the wide end of said base being provided with inclined beveled faces, a clamp arranged around the inclined faces to hold the ends of the necktie thereto, the upper reduced end of said base provided with an axial bore, springs seated in said bore, a plunger fitted in said bore and resting upon said spring, a cross arm connected to the outer end of said plunger, means connected to the upper end of the base and engaging the plunger to hold the same in against the tension of said spring, said cross arm adapted to receive the central portion of a tie thereover, and when released, the same will be stretched.
- 10 2. A necktie stretcher including a base, said base tapering toward one end, said reduced end provided with an axial bore, the opposite enlarged end of said base being bevelled to present inclined faces, a clamp 25
- 15 around said inclined faces of the large end, a spring seated in said axial bore, a plunger in said bore, its lower end engaging the upper end of the said spring, its free end extending outwardly beyond the edges of said bore, a cross arm on the outer end of said plunger, said arm adapted to receive the central portion of a tie and the ends of said tie secured under the clamp at the wide end 30
- 20 of the base, and means secured to the reduced end of the base engaging the cross arm for holding the same inward against the tension of the spring to permit the tie to be placed over the cross arm, and means for limiting the outward movement of said 35 plunger.

In testimony whereof I affix my signature in presence of two witnesses.

HENRY P. EASTMAN.
